UNITED STATES PATENT OFFICE.

CHARLES W. MERCIER, OF NEWARK, NEW JERSEY, ASSIGNOR TO THE WHITEHEAD & HOAG COMPANY, OF NEWARK, NEW JERSEY, A CORPORATION OF NEW JERSEY.

BANK.

Application filed February 18, 1919. Serial No. 277,850.

To all whom it may concern:

Be it known that I, CHARLES W. MERCIER, of Newark, N. J., in the county of Essex, in the State of New Jersey, have invented 5 new and useful Improvements in Banks, of which the following, taken in connection with the accompanying drawings, is a full, clear, and exact description.

This invention relates to certain new and 10 useful improvements in banks and pertains particularly to savings banks of the small portable type adapted to be carried about in a person's pocket and into which coins may readily be inserted and be withdrawn 15 therefrom only upon opening the bank by the use of a suitable tool in the hands of someone familiar with the locking mechanism, this type of bank being commonly employed by savings banks institutions for 20 distribution among its customers, as an advertising novelty.

The general object of the invention is to produce a savings bank of small size and of relatively simple and inexpensive construction and which will be highly efficient 25 for the purpose designed.

Specific objects and advantages relate to and reside in the details of construction of the bank, with particular reference to the 30 mechanism for removably locking the parts together, all of which will more definitely appear from the following description taken in connection with the accompanying drawings in which—

35 Figure 1, is a perspective view of a bank of this invention.

Figure 2, is a cross-section on line 2—2

Figure 3.

Figure 3, is a cross-section on line 3—3

Figure 10, is a cross-section on line 10—10

Figure 8.

55 The invention as shown comprises a cup-

shaped body—1, the base—2—of which is substantially flat while the vertical side wall—3—is substantially cylindrical. The wall—3—is provided with a series of outwardly punched lugs—4—for retaining a base ring—5—which ring is adapted in turn to be interlocked with and retain a flanged base cap—6—and preferably, as shown the base cap is provided with a covering of suitable material such as celluloid or the like for receiving or displaying advertising or other matter and in the specific illustration the edge of the celluloid sheet—7—is wrapped about the flanged edge of the base cap—6—and is confined between the flange—8—upon the base cap and base ring—5. The base ring—5—constitutes a continuous circular bearing surface for the base cap—6.

The vertical side wall—3—near its upper edge is provided with a plurality of spaced openings elongated circumferentially of the wall—3—. The slots or openings—9—and—10—are adapted to receive lugs—11—and—12—respectively formed upon and extending inwardly from a lid ring—13—while an opening or slot—14—is adapted to receive and permit free radial movement of flange—15—formed upon a member—16—which may be formed of thin sheet metal of desired resiliency or flexibility to permit of the operation hereinafter described. This member—16—comprises a horizontal base portion—17—and a vertical part—18—upon the upper end of which the flange—15—is formed. The member—16—may be secured to the base—2—of body—1—in any suitable way and as shown is provided with spaced openings, through which lugs—19—punched from the base may be passed and then clenched in opposed directions into contact with the upper surface of base portion—17—. Under normal conditions the member—16—is so formed that the flange—15—extending through opening—14—projects a short distance from the outer surface of wall—3—so as to engage the in-turned flange—20—upon the lower edge of lid ring—13—. The lid ring is provided with a suitable cover—21—secured thereto in any suitable manner and as shown the diameter of the lid ring increases upwardly while the cover is provided with a circular flange—22—telescoped externally therewith and preferably the cover—21—in like man-

ner as the base cap—6—has a covering—24—of material such as celluloid adapted to carry or display advertising matter or the like and the edge of the sheet may preferably be disposed between lid ring—13—and flange—22. The lid ring—13—and cover—21—either with or without the celluloid or other facing constitute the removable lid of the bank. The operation of this structure will be readily understood. When the flanges—11—and—12—are positioned in openings—9—and—10—they constitute a limited hinge about which certain relative movement of the lid and body—1—may be had. When the flange—15—is pressed back so as not to project beyond the exterior surface of wall—3—then lid ring—13—may be externally telescoped with the wall—3—and when the flange—15—is released it will move outwardly under the spring tension of its supporting member—16—and lie above the lower edge of flange—20—to prevent separation of the lid of the bank from the body thereof. The wall—3—of the bank at a point preferably adjacent member—16—is provided with an elongated coin slot—25—which may as shown have a flexible or movable interior covering 25' to prevent removal of coins through the coin slot. A suitable tool may be inserted through the coin slot and pushed between the part—18—and the adjacent portion of wall—3—to increase the spaced distance of these parts, and withdraw the flange—15—to such an extent that it no longer projects from the wall—3—thereby permitting the lid to be moved about the flanges—11—and—12—to a position of such angular disposition relatively to body—1—that the flanges—11—and—12—can be withdrawn from the respective openings in wall—3—and the lid and body of the bank separated.

In Figures 7 to 10 inclusive, I have illustrated a slightly modified form of structure in that instead of the openings—9—and—10—formed in wall—3—, such wall is provided with a pair of spaced outwardly projecting flanges of a suitable radial length to permit suitable engagement with the flange—20—upon the lid ring—13. These externally projecting flanges—26—and—27—engage the flange upon the lid ring and permit the same hinging operation as is effected by the structure of the former figures. These flanges—26—and—27—may be integral parts of the side wall—3—and may as shown be formed by forming spaced slits in the side wall and then bending the portion intermediate the slits, outwardly and forming it of the desired radial length. In this disclosure the base—17—is of slightly different shape than the base—17—of the former figures and one of the flanges—19—is utilized to hold the flexible covering 25' in place across the coin slot.

Altho I have shown and described specific construction of bank as perhaps constituting preferred embodiments of my invention, I do not desire to limit myself to the details of construction, form or arrangement 70 of the parts except as specifically set forth in the claims hereto appended.

What I claim is:

1. A coin receptacle comprising a substantially cup-shaped body having a pair of 75 adjacent openings in its side wall and a third and oppositely disposed opening in said side wall, a cap having an inwardly extending flange telescoped externally with said body, said cap embodying a pair of 80 adjacent radially and inwardly extending lugs projecting respectively thru one of said pair of adjacent openings, and a movable locking member positioned within and secured to the base, and having a portion 85 extending outwardly thru said third opening and engaging the upper surface of the inwardly extending flange on said cap to removably lock the cap and base together.

2. A coin receptacle comprising a substantially cup-shaped body having a pair of 90 adjacent openings in its side wall and a third and oppositely disposed opening in said side wall, a cap having an inwardly extending flange telescoped externally with 95 said body, said cap embodying a pair of adjacent radially and inwardly extending lugs projecting respectively thru one of said pair of adjacent openings, a movable locking member positioned within and secured 100 to the base, having a portion extending outwardly thru said third opening and engaging the upper surface of the inwardly extending flange on said cap to removably lock the cap and base together, said base 105 provided with a coin slot permitting access to said movable member whereby said member may be disengaged with the cap.

3. In a receptacle a cover section comprising a disk having a flange along its 110 edge, covering material extending over one face of said disk, and around said flange, and along the inner surface thereof, a lid ring telescoping within said flange on said disk and fitting against a portion of the 115 said covering material which extends along the inner surface of said flange, said lid ring including a ring-shaped portion formed at its outer edge with an inwardly extending circumferential flange disposed at 120 an angle to said ring-shaped portion, and a cup-shaped casing fitting within the lid ring and removably connected to said cover section.

In witness whereof I have hereunto set 125 my hand this 7th day of February, 1919.

CHARLES W. MERCIER.

Witnesses:

CHAS. R. CRONCE,
GEORGE HOWARD.
